CLAIM

The ornamental design for a hardtop for a vehicle as shown and described.

DESCRIPTION

FIG. 1 is a front elevational view of a hardtop for a vehicle; FIG. 2 is a right side elevational view of the embodiment of FIG. 1;

FIG. 3 is a rear elevational view of the embodiment of FIG. 1;

FIG. 4 is a front perspective view of the embodiment of FIG. 1;

FIG. 5 is a rear perspective view of the embodiment of FIG. 1;

FIG. 6 is a right side perspective view of the embodiment of FIG. 1; and,

FIG. 7 is a rear perspective view of the embodiment of FIG. 1.

The right side elevational views are mirror images of the left sides.

1 Claim, 7 Drawing Sheets
